UNITED STATES PATENT OFFICE.

ADOLPH A. SPECHT, OF QUINCY, ILLINOIS, ASSIGNOR TO GEM CITY STOVE MANUFACTURING COMPANY, OF QUINCY, ILLINOIS, A CORPORATION.

DESIGN FOR A STOVE FIRE-POT SECTION AND BASE.

44,733.

Specification for Design.

Patented Oct. 14, 1913.

Application filed June 14, 1913. Serial No. 773,768. Term of patent 14 years.

To all whom it may concern:

Be it known that I, ADOLPH A. SPECHT, a citizen of the United States of America, residing at Quincy, in the county of Adams and State of Illinois, have invented a new, original, and ornamental Design for a Stove Fire-Pot Section and Base, of which the following is a specification, reference being had to the accompanying drawing, forming part thereof.

The figure is a perspective view, showing my new design.

I claim:

The ornamental design for a stove fire pot section and base, as shown.

ADOLPH A. SPECHT.

Witnesses:

W. F. THOMPSON,
NEVADA S. PROCTOR.
